UNITED STATES PATENT OFFICE.

ELMER S. SHIMER, OF MILTON, PENNSYLVANIA.

SPACING-ESCAPEMENT AND CARRIAGE-FEEDING MECHANISM FOR TYPE-WRITING MACHINES.

SPECIFICATION forming part of Letters Patent No. 654,029, dated July 17, 1900.

Application filed April 20, 1900. Serial No. 13,619. (No model.)

To all whom it may concern:

Be it known that I, ELMER S. SHIMER, a citizen of the United States, residing at Milton, in the county of Northumberland and State 5 of Pennsylvania, have invented new and useful Improvements in Spacing-Escapements and Carriage-Feeding Mechanisms for Type-Writing Machines, of which the following is a specification.

10 My invention relates to spacing-escapements and carriage-feeding mechanisms for type-writing machines; and the objects of the same are to provide a simple, efficient, and easily operated rack-and-pinion spacing- 15 escapement and reliable means for disengagement thereof to permit the carriage to be shifted or returned at the end of each line printed. I attain these objects by means of the construction shown in the accompanying 20 drawings, which form a part of this specification, and in which—

Figure 1 is a plan view of so much of a type-writing machine as will serve to illustrate my improvements. Fig. 2 is a rear elevation of 25 the mechanism. Fig. 3 is a vertical section through the frame. Fig. 4 is a detail perspective view of the spacing-rack and contiguous parts. Fig. 5 is a side view of the pinion and clutch. Fig. 6 is a detail section of the 30 escapement-wheels.

Like characters designate like parts wherever they occur in the different views.

The numeral 1 designates the guide-rail for the carriage. This rail is provided with central longitudinal grooves 2, which form a race-way for the balls 3, supported in channeled bars 4, rigidly attached to the frame of the machine. The carriage is pivoted to the guide-rail 1 upon lugs 5, which extend forward 35 from said guide-rail. Lugs 6 extend to the rear from guide-rail 1. The rack 8 is provided with arms 9, pivotally connected to a rod 7. Secured to the upper surface of the rack 8 and projecting outward beyond the teeth 10 is a plate 11, extending longitudinally 40 the full length of said rack. The vertical spacing-shaft 12 is journaled at its lower end in a plate or bracket 13 and near its upper end is supported in a plate 14, secured to the top of the table *a* of the machine. Secured 45 to said spacer-shaft, near the lower end thereof, by means of a set-screw 15^a is an escape-

ment-wheel 15, formed with two opposite slots 16 and with an elongated opening 17. Secured to this wheel is one end of a coiled 55 spring 18, the other end of which is secured to a loose escapement-wheel 19, located below the wheel 15 and journaled on said shaft 12. This wheel is provided with an opening 20, which coincides with the opening 17, the 60 object of these openings being to accommodate the spring 18. Secured to said wheel 19 are two upwardly-extending headed screws 21, which pass through the slots 16, said slots being slightly larger than the shanks of 65 the screws 21, so as to allow said wheels to have an alternate intermittent movement for feeding the carriage to make the letter and word spaces, as will be described. The screws and slots bear such relation to each other 70 and to the wheels that as a key is depressed the loose wheel will move a distance a fraction less than the fixed wheel and will complete its stroke when the key is released, at which time the fixed wheel and its shaft 75 will move a distance equal to a letter-space, this movement being effected through the medium of the carriage-driving spring. A pawl 21^a, mounted rigidly on a rock-shaft 22, engages the teeth 23 on the wheels 15 and 80 19, and the rock-shaft is journaled at its ends in the frame of the machine and is operated by the type-bars 24. Lugs 25 extend outward from the rock-shaft, and connecting-rods 26 are attached to the lugs 25 and to the cross- 85 bar 27, located immediately under the key-bars 24, so that when any of the keys are struck the rock-shaft will move the pawl 21^a and permit the escapement-wheel to move the distance of one tooth. A spring 21^b returns 90 the rock-shaft 22 to its original position. Journaled loosely upon shaft 12, near its upper end, is a pinion 28, having an upper ratchet-face 29 and a groove 30 between the pinion and ratchet. The teeth of the rack 8 fit the 95 cogs on the pinion 28, and the plate 11 rests in the groove 30 at the top of the pinion. The ratchet-face 29 is held in mesh with the rigidly-fixed ratchet 31 by the spiral spring 32, which surrounds the shaft 12 and rests at 100 its lower end on a collar 33, adjustably fixed to the shaft by a set-screw 34. The upper end of the spring bears upon the lower face of the pinion 28. A lever 35, pivoted at 36

to the frame of the machine, has an arm 37, which normally rests on one of the arms 9^a of the rack, and when the lever is actuated against the stress of its spring 38 the arm 37 5 bears upon a button 37^a and the rack is depressed and the plate 11 pushes the pinion down and disengages the ratchet-face 29 from the ratchet 31. The carriage may then be moved in either direction, the pinion being 10 free to revolve in either direction, the cogs on the pinion always fitting the teeth of rack 8.

The operation is as follows: When it is desired to shift the carriage, the lever 35 is actuated against the tension of spring 38, 15 the arm 37 then riding over the end of arm 9^a and sliding up over the button 37^a, thus depressing the plate 11 sufficiently to release the ratchets 29 31 and permit the carriage to be shifted.

20 Having thus fully described my invention, what I claim is—

1. In a type-writing machine, a carriage-feeding mechanism consisting of a vertical spacing-shaft and means to rotate it intermittently, a pinion loosely mounted on said shaft, a ratchet-face on the pinion, a ratchet with which it engages, a rack in mesh with the pinion, and a plate secured to and projecting over the rack for disengaging the 25 ratchet to shift the carriage, substantially as described.

2. In a type-writing machine, a vertical spacing-shaft having escapement-wheels thereon, adapted to be actuated by a rock-shaft controlled by the key-bars, a pinion 35 on the spacing-shaft, said pinion carrying a ratchet-face and having a groove formed between the ratchet-face and pinion, a rack meshing with the pinion, a plate secured to and projecting over the rack, said plate sliding in the groove, and means for depressing the plate to disengage the ratchet to permit the carriage to be shifted.

3. A carriage-feeding mechanism for type-writing machines, consisting of a rack, a 45 pinion in mesh with said rack and loosely journaled on a vertical spacing-shaft, a ratchet carried by the pinion, a spring for holding the ratchet in engagement, and a plate secured to said rack and projecting beyond the teeth thereof for depressing the pinion to release the ratchet to permit the carriage to be shifted, substantially as described.

In testimony whereof I have hereunto set 55 my hand in presence of two subscribing witnesses.

ELMER S. SHIMER.
